UNITED STATES PATENT OFFICE

121,470

DESIGN FOR A DOUGHNUT

Roy S. Fox, York, Pa., assignor to Edw. Fox
Baking Co., Inc., York, Pa., a corporation of Pennsylvania

Application May 14, 1940, Serial No. 92,373

Term of patent 14 years

To all whom it may concern:

Be it known that I, Roy S. Fox, a citizen of the United States, residing in Wyndham Hills, York, Pennsylvania, have invented a new, original, and ornamental Design for a Doughnut, of which the following is a specification, reference being had to the accompanying drawing, forming part thereof, in which:

Fig. 2 is an end view.

I claim:

The ornamental design for a doughnut, substantially as shown.

ROY S. FOX.
